UNITED STATES PATENT OFFICE.

PETE DE SALVO, OF HOUSTON, TEXAS.

ARCH SUPPORT.

Application filed October 2, 1923. Serial No. 666,049.

This invention relates to new and useful improvements in an arch support.

One object of the invention is to provide an arch support for supporting fallen arches 5 of the human foot, and which embodies means for securing the support in proper position in the arch of the foot.

Another object of the invention is to provide an arch support formed with an up- 10 standing inside wing, adapted to fit closely against the inside of the foot to more effectively support the arch.

A further feature resides in the provision of an arch support within which there is incor- 15 porated a metallic strip of arched contour which strengthens and preserves the form of the support.

With the above and other objects in view, the invention has particular relation to cer- 20 tain novel features of construction, arrangement, of parts, and use, an example of which is given in this specification, and illustrated in the accompanying drawings, wherein:—

Figure 1 shows a plan view of the support. 25

Figure 2 shows a perspective view, showing the two bottom plies drawn back to reveal the interior structure of the support.

Figure 3 shows a longitudinal sectional view taken on the line 3—3 of Figure 2; and, 30

Figure 4 shows a cross sectional view taken on the line 4—4 of Figure 1.

In the drawings, the numeral 1 designates the top ply of the support. This ply is preferably formed of thick leather which is 35 softened by soaking in water and then moulded to the required form, and when dried is comparatively rigid. As shown this ply is arched to conform to the normal arch of the human foot, and its inner side is up- turned, forming the inside wing 2, to fit up 40 against the inside of the foot, and support

the same. There is a long, comparatively narrow, arched, metallic strip 3 fastened lengthwise to the bottom of ply 1, and glued, or otherwise secured, over this strip, to the 45 bottom of the top ply; there is the bottom ply 4, of somewhat smaller area than the top ply, but formed in the same manner, and of the same material as the top ply.

There is a suitable sheath 5, forming an 50 outer covering for the support, and formed of thin smooth leather.

The support thus formed will have sufficient rigidity to support a fallen arch, but yet will have sufficient flexibility to yield in 55 walking so as not to make it uncomfortable, and to accommodate itself to the necessary movements of the foot in walking.

The support is secured to the foot by means of a strap 6, which is fastened at 60 one end to the wing 2, and which passes around the ankle and whose free end may be secured to said wing by suitable releasable securing means, as by the lace 7.

What I claim is:

65 An arch support formed with an inside upturned wing and having a plurality of lengthwise, strips or plies, a lengthwise metallic strip incorporated in its structure and between said lengthwise strips, a strap attached only to the inside of said wing near its free edge and intermediate its ends, said strap being adapted to surround the ankle of the wearer means for securing the free end of said strap to the free edge of said 70 wing, said strap being provided to hold the support in its proper position and adapted to prevent lateral movement of the support 75 toward the outside of the foot.

In testimony whereof I have signed my 80 name to this specification.

PETE DE SALVO.
